Primary Examiner — Wan Laymon*Assistant Examiner* — Clint A Samuel(74) *Attorney, Agent, or Firm* — Nixon & Vanderhye(57) **CLAIM**

The ornamental design for a light diffuser, as shown and described.

DESCRIPTION

FIG. 1 is a front, left side, and top perspective view of a light diffuser showing the new design;

FIG. 2 is a front, left side, and bottom perspective view thereof;

FIG. 3 is a top plan view thereof;

FIG. 4 is a bottom plan view thereof;

FIG. 5 is a right side elevation view thereof, wherein the left side elevation view appears the same in mirror image; and, FIG. 6 is a front elevation view thereof, wherein the rear elevation appears the same in mirror image.

The broken lines shown in the drawings illustrate portions of the light diffuser that form no part of the claimed design.
